MYRENS VERKSTED, OF CHRISTIANIA, NORWAY.

WET CENTRIFUGAL COMPRESSOR.

1,385,318.

Specification of Letters Patent. Patented July 19, 1921.

Application filed March 6, 1920. Serial No. 363,671.

To all whom it may concern:

Be it known that I, JENS WILLIAM AEGIDIUS ELLING, a subject of the King of Norway, residing at Christiania, Norway, have 5 invented certain new and useful Improvements in Wet Centrifugal Compressors, for which I have filed application in Norway, Application No. 15609, filed Feb. 11, 1919; and I do hereby declare the following to be 10 a full, clear, and exact description of the invention, such as will enable others skilled in the art to which it appertains to make and use the same, reference being had to the accompanying drawings, and to figures of 15 reference marked thereon, which form a part of this specification.

The present invention relates to centrifugal compressors of the kind in which the medium to be compressed, for instance steam or air, is mixed with a certain amount of 20 water in order to increase the effect of the centrifugal force and obtain a high compression by means of a small number of stages.

In order to obtain the best possible effect 25 with centrifugal compressors of this type the amount of water added to the medium to be compressed should be sufficient to produce a kind of foam, in which the medium to be compressed forms the bubbles. If too 30 little water is added, the mixture will be more like a mist, in which the water forms small separate particles, whereby the desired effect is not obtained.

It will be understood that during the 35 process of compression the volume of the compressible medium decreases while the volume of liquid remains unaltered, and accordingly if sufficient liquid is added to the medium at the beginning of compression, 40 there will be far too much liquid in the mixture when the compression process is finished. In this case obviously a large amount of work will be wasted in carrying the superfluous amount of liquid up to the high 45 pressure.

In order to obviate this drawback a certain amount of the liquid according to the present invention added to the medium to be compressed is separated from the mixture 50 after each stage of the compressing process and is returned to the beginning of the same stage.

Accordingly there may be introduced into 55 the compressor only the amount of liquid necessary in the last stage of the compressing

process, while in other stages of the process the further amount of liquid needed is kept circulating between the beginning and end of the said stage.

On the drawing is diagrammatically illustrated a part of a compressor built on the above mentioned principle.

1 is a mixing chamber, where the medium to be compressed enters through intake 10 and is mixed in the usual manner with water 65 or a similar liquid from a separating chamber 2 above the mixing chamber 1. Water is added to the mixing chamber 2 through a supply pipe 9.

Above the outlet openings 3 of the separating chamber 2 there is located a horizontal baffle plate 4 in order to give the water a radial movement toward the outlet and to prevent the escape of air from the separating chamber.

5 is the first rotorwheel of the centrifugal compressor. The mixture is pumped from this first stage of the compressor through pipe 6 up to the separating chamber 2 from which the medium to be compressed is conducted away through pipe 7 leading to the next rotorwheel 8 of the compressor. From this stage the mixture with its reduced volume of water may be pumped to a second compressor (not shown) like the first one, 85 through a pipe 11, or the mixture may be blown into the atmosphere without influencing the function of the apparatus.

Claims:

1. The process of compressing a gaseous 90 medium, which comprises adding to the medium before compression an amount of liquid, compressing the mixture, separating part of the liquid from the mixture after compression, and returning the separated 95 liquid to the compressor.

2. The process of compressing a gaseous medium, which comprises adding to the medium before compression sufficient water to produce a foam, compressing the mixture, 100 separating part of the added liquid from the mixture after compression, and returning the separated liquid to the compressor.

3. The process of facilitating the compression of a gaseous medium, which consists in introducing into the medium to be compressed before the first stage of compression an amount of liquid sufficient for the last state of compression, and circulating a certain amount of liquid between the 110

- beginning and end of each stage of compression, whereby a sufficient amount of liquid in the mixture is maintained in the mixture at all stages of the process.
- 5 4. An apparatus for compressing a mixture of gas and liquid, comprising two compressor stages; a mixing chamber, a separating chamber, and means including the compressor stages whereby a certain amount of the liquid is separated from the mixture between the stages.
5. An apparatus for compressing a mixture of gas and liquid, comprising a mixing

chamber, a separating chamber, means for compressing and conducting a mixture of 15 gas and liquid from the mixing chamber to the separating chamber, and means for conducting a part of the liquid of the mixture from the separating chamber.

In testimony that I claim the foregoing 20 as my invention, I have signed my name in presence of two subscribing witnesses.

JENS WILLIAM ÆGIDIUS ELLING.
